(57) **CLAIM**

The ornamental design for an impact wrench, as shown and described.

DESCRIPTION

FIG. 1 is a left/front perspective view of an impact wrench.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top view thereof; and,

FIG. 7 is a bottom view thereof.
